[57] CLAIM

The ornamental design of a railing flower pot holder, as shown and described.

DESCRIPTION

FIG. 1 is a perspective view of a railing flower pot holder showing my new design;

FIG. 2 is a top plan view thereof;

FIG. 3 is a front elevation view thereof;

FIG. 4 is a right side elevation view thereof, the left side elevation view thereof being a mirror image;

FIG. 5 is a rear elevation view thereof;

FIG. 6 is a bottom plan view thereof; and,

FIG. 7 is a perspective view thereof showing an alternate embodiment.

*Fig. 1**Fig. 2**Fig. 3**Fig. 4**Fig. 5**Fig. 6**Fig. 7*
